UNITED STATES PATENT OFFICE.

WILLIAM MISCHLER, OF BROOKLYN, NEW YORK, ASSIGNOR TO E. G. WEBSTER & SON, INC., A CORPORATION OF NEW YORK.

DESIGN FOR A PITCHER.

48,354.

Specification for Design.

Patented Dec. 28, 1915.

Application filed October 14, 1915. Serial No. 55,902. Term of patent 7 years.

To all whom it may concern:

Be it known that I, WILLIAM MISCHLER, a citizen of the United States, and a resident of the borough of Brooklyn, county of Kings, and State of New York, have invented a new, original, and ornamental Design for a Pitcher, of which the following is a specification, reference being had to the accompanying drawings, forming a part hereof.

I claim:

The ornamental design for a pitcher, substantially as shown.

WILLIAM MISCHLER.

Witnesses:

HENRY V. RAYMOND,
ALBAN E. McKEAN.
